UNITED STATES PATENT OFFICE.

JOSEPH LOUIS PANCOAST, OF TRENTON, NEW JERSEY.

LOCKING-BOLT.

1,217,878.

Specification of Letters Patent. Patented Feb. 27, 1917.

Application filed June 2, 1916. Serial No. 101,359.

To all whom it may concern:

Be it known that I, JOSEPH LOUIS PANCOAST, a citizen of the United States, residing at Trenton, in the county of Mercer, 5 State of New Jersey, have invented certain new and useful Improvements in Locking-Bolts; and I do hereby declare the following to be a full, clear, and exact description of the invention, such as will enable others 10 skilled in the art to which it appertains to make and use the same.

This invention relates to locks and latches and has special reference to a locking bolt peculiarly adapted for use in locking shutters and other outside house closures which 15 are apt to be interfered with by unauthorized persons.

One object of this invention is to provide a device of this description which is so arranged that no matter how slightly the bolt 20 may be engaged in its keeper the releasing of the operating handle will lock the bolt firmly in such engagement.

Another object of the invention is to provide 25 a locking device for sliding the bolt which is adapted for use in connection with a bolt so arranged within its casing that no rotative movement of the bolt is possible, thus preventing releasing of the locking device by unauthorized persons as can readily 30 be done by the ordinary form of sliding and rotating bolts.

With the above and other objects in view, as will be hereinafter apparent the invention 35 consists in general of certain novel details of construction and combinations of parts hereinafter fully described, illustrated in the accompanying drawing, and specifically claimed.

40 In the accompanying drawing, like characters of reference indicate like parts in the several views, and:—

Figure 1 is a front elevation of the device applied to a pair of shutters; the major portion of said shutters being broken away and only those portions directly adjacent the bolt and its keeper being shown; 45

Fig. 2 is a section on the line 2—2 of Fig. 1;

50 Fig. 3 is a section on the line 3—3 of Fig. 1;

Fig. 4 is a bottom view of the bolt casing showing the teeth thereon.

The invention as herein disclosed is shown 55 as applied to a pair of shutters A although it is obvious that the bolt may be used in

connection with any two objects of like character such as a door and its jamb, a window and its casing or the like.

The invention itself consists of a casing 10 the main portion of which is polygonal in cross section and from the edges of this casing project the flanges 11 by means of which the casing is supported against the shutter. Through these flanges 11 extend 15 the screws 12 to secure the casing to the shutter. This casing is furthermore provided on its front side with a slot 13 extending longitudinally of the casing. Slidable within the casing 10 is a bolt 14 which 20 conforms in cross section to the cross section of the casing so that it can not be rotated therein. Fixed to this bolt 14 is a U-shaped pivot loop or staple 15 and the bight of this staple projects through the 25 slot 13. Pivotedly mounted on this staple 15 is an operating handle 16 which may be swung into horizontal position to move the bolt, and which, when released will drop 30 under the influence of gravity until the handle assumes the position shown in Fig. 3, the lower end of the handle resting against the lower part of the casing. Projecting from this handle 16 is a lug 17 which is provided on its upper surface with one or more 35 teeth 18. When the handle is in the position shown in Fig. 3 the lug will project beneath the casing and the teeth 18 will engage one or more of the teeth 19 formed on the under side of the casing. Both of 40 the sets of teeth are preferably V-shaped although other forms may be used, if desired.

At 20 is shown a keeper which is of suitable shape and size to receive the ends of 45 the bolt 14 when in locked position.

In operation, let it be supposed that the bolt is open or in unlocked position. The handle 16 is then raised until the handle is brought to horizontal position when the bolt may be slid forward into the keeper. When engaged in the keeper the handle is 50 released and will drop to the position shown in Fig. 3 so that the teeth 18 and 19 engage and prevent movement of the bolt in either direction. It is to be noted that the teeth 19 extend along the underside of the casing to a length sufficient to enable the teeth 18 to engage therewith at any point in the movement of the bolt and thus the locking 55 of the bolt is entirely accomplished by gravity.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

What is claimed is:—

1. In combination, a casing having a slot formed in its outer side, a bolt slideable in the casing, a handle pivoted to the bolt for vertical swinging movement and projecting through the slot, a series of teeth projecting downwardly from the under side of the casing, and a toothed lug on the handle, extending beneath the casing with its toothed portion engaging the casing teeth upon depression of the handle.
2. In combination, a casing polygonal in cross-section and having a slot formed in its outer side, a bolt slideable in the casing, a handle pivoted to the bolt for vertical swinging movement and projecting through

the slot, a series of teeth projecting downwardly from the under side of the casing, and a toothed lug on the handle, extending beneath the casing with its toothed portion engaging the casing teeth upon depression of the handle.

3. In combination, a casing polygonal in cross-section and having a slot formed in its outer side and extending longitudinally of the casing, a polygonal bolt slidably fitted in the casing, a pivot loop fixed to the bolt and projecting through the slot, an operating and locking handle pivoted on the loop and arranged to be positioned horizontally to operate the bolt and vertically to lock the bolt, V-shaped teeth formed on the under side of the casing, and a lug on the handle arranged to project beneath the casing when the handle is in vertical position, said lug being toothed to engage the teeth on the casing.

In testimony whereof I affix my signature, in the presence of two witnesses.

JOSEPH LOUIS PANCOAST.
